(57) **CLAIM**

The ornamental design for a cartridge for sample analysis, as shown and described.

DESCRIPTION

FIG. 1 is a top perspective view of a cartridge for sample analysis showing our new design;

FIG. 2 is a bottom perspective view thereof;

FIG. 3 is a top view thereof;

FIG. 4 is a side view thereof;

FIG. 5 is bottom view thereof;

FIG. 6 is another side view thereof;

FIG. 7 is front view thereof; and,

FIG. 8 is rear view thereof.

The alternate long and short broken lines in FIGS. 1-7 represent the bounds of the claim. The other broken lines in the drawing views are included for the purpose of illustrating portions of the cartridge for sample analysis that form no part of the claimed design. None of the broken lines form a part of the claimed design.
